UNITED STATES PATENT OFFICE.

ERNEST L. CORAM, OF BUFFALO, NEW YORK.

DESIGN FOR A MATCH-SAFE.

SPECIFICATION forming part of Design No. 34,497, dated May 14, 1901.

Application filed April 20, 1901. Serial No. 56,791. Term of patent 3½ years.

To all whom it may concern:

Be it known that I, ERNEST L. CORAM, a subject of the King of Great Britain, residing at Buffalo, in the county of Erie and State of New York, have invented and produced a new and original Design for a Match-Safe, of which the following is a specification, reference being had to the accompanying drawings, forming part thereof.

10 This design relates to the formation and configuration or ornamentation of a match-safe or similar article, as is clearly shown in the accompanying drawings, in which—

Figure 1 is a face view of the design. Fig. 15 2 is a top plan view of the same.

The design consists of a shield having the representation of a buffalo's head projecting therefrom, and formed centrally in the top of said head is a cavity or receptacle for matches, 20 &c. On the shield, above the buffalo's head, is the representation, in relief, of a ribbon

having a curved center portion and downwardly-flowing scalloped ends.

Referring to the drawings, A is the representation of a shield, B is the representation 25 of a buffalo's head projecting from the face of the shield, and C is a cavity located centrally in said head. Projecting from the shield, directly above the said head, is a ribbon D, which has its ends scalloped and arranged to extend down at either side of the projecting buffalo's head.

Having thus described my invention, what I claim is—

The design for a match-safe or similar article, substantially as herein shown and described.

ERNEST L. CORAM.

In presence of—

M. A. GIBBS,
CHAS. F. BURKHART.
